UNITED STATES PATENT OFFICE.

CHARLES R. MOORE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

TELEPHONE TRANSMITTER.

Application filed October 17, 1923. Serial No. 689,028.

This invention relates to telephone transmitters the object being to provide an efficient and inexpensive transmitter capable of translating sound waves into electrical waves with minimum distortion.

In accordance with the general features of the invention there is provided a structure in which the moving parts are light but rigid and are so mounted that they will respond accurately and readily to all vibrations within the normal sound range. More specifically the invention comprises a light sound responsive diaphragm in the form of a double cone suitably supported to permit full translation of sound vibrations and cooperating with a microphonic button the closure of which is a double cone diaphragm suitably mounted for damping and having its apex in contact with the apex of the sound responsive diaphragm.

In the drawings in which the invention is illustrated as applied to a push-pull transmitter, Fig. 1 represents a cross section of a transmitter embodying the invention.

Fig. 2 illustrates a circuit in which the transmitter may be used.

As shown in the drawings, face plate 3 is provided with an internally threaded flange at its periphery and oppositely projecting concentric flanges 5 and 6. Flange 5 is provided with internal threads to adjustably receive the microphone unit 7 and flange 6 is threaded for the usual mouth piece 8. Between the flanges 5 and 6 are a series of perforations 9 for the purpose of permitting the sound waves to reach the diaphragm which preferably consists of two conical-shaped discs 10 and 11 held together at their peripheries by means of a number of thin paper or foil rings 12 loosely clamped between the face plate 3 and a rear plate 13 having an externally threaded flange 33 at its periphery engaging the flange 4 on the face plate 3. The total thickness of the rings 12 and the discs 10 and 11 of the diaphragm should be somewhat less than the distance between the plates 3 and 13 at this point in order to permit substantially free translation of the diaphragm. The rear plate 13 has a threaded flanged aperture 14 in which a microphone unit 15, similar to microphone unit 7, is adjustably secured. To the microphone unit 7 is attached a dome-shaped shell 16 for directing the sound waves through the openings 9.

The microphone units 7 and 15 are preferably of the barrier type in which the electrodes 17 and 18 forming the inner peripheral walls are separated by a ring-shaped barrier 19 of insulating material. The rear walls 20 and electrodes 18 are suitably insulated from their cups 34. The inner surfaces of the rear walls 20 are also preferably given a coat of insulating compound to insulate them from the granular material. Conical closures are provided for the microphone units. Preferably each closure comprises two small cone-shaped discs 21 and 22 supported against each other at their peripheries by means of paper or foil rings 23, a number of which are loosely disposed on each side of the diaphragm and supported in place by the clamping rings 24 which seat on an annular spacer member 35, which may be integral with the electrodes 17. The thickness of the spacer member 35 should be slightly greater than the total thickness of the rings 23 and the discs 21 and 22. The apexes of the closures abut against apexes of the diaphragm and require no further connection. The contact pressure between the diaphragm and the closures may be controlled by adjusting the microphone units 7 and 15 in the plates 3 and 13. Lock nuts 25 may be provided to lock them in place after adjustment. The electrodes 17 may be grounded to the case and the common lead 26 connected thereto. An insulated terminal 27 may be mounted on a face plate 3 for connecting the electrodes 18 in the microphone unit 7 to line 28 and similarly the electrode 18 of the microphone 15 may be connected to the line 29.

The inner surfaces of the conical discs 22 and the walls 20 exposed to the granular material are preferably given a coat of insulating material. The diaphragm members 10 and 11 and the closure members 21 and 22 are preferably made up of thin sheet aluminum or its alloys.

The circuits shown in Fig. 2 is the usual push-pull type circuit in which 1 is the transmitter, 26, 28 and 29, the connections thereto, 30 the source of electric current, 31 the induction coil and 32 the receiver.

What is claimed is:

1. In a transmitter, a sound responsive diaphragm, a carbon containing chamber and a conical-shaped closure of sheet material for said chamber, the apex of said clo-

- sure making contact with said diaphragm.
2. In a transmitter, a conical diaphragm, a chamber for granular material, a conical closure therefor, and means for supporting 5 said diaphragm and said closure in contact at their apexes.
3. In a transmitter, a diaphragm having a convex surface, a chamber for granular material, a closure for said chamber having 10 a convex surface, and means for supporting said diaphragm and said closure in contact at the centers of their convex surfaces.
4. In a transmitter, a double conical diaphragm, a chamber for granular material 15 on each side of said diaphragm, a conical closure for each chamber, and means for supporting said diaphragm and said closures in contact at their apexes.
5. In a transmitter, a hollow conical diaphragm, formed of two conical members, a chamber for granular material on each side of said diaphragm, a hollow closure for each chamber formed of two conical members, and means for supporting one member 20 of each closure in contact with said diaphragm at their apexes.
6. In a transmitter, a double conical diaphragm of thin sheet material, a casing therefor, a plurality of rings of thin material 25 loosely disposed on each side of said diaphragm between its periphery and said casing, a pair of microphone units adjustably supported in said casing, a double conical closure of thin material for each unit, a plurality of rings of thin material loosely 30 disposed on each side of each closure at its periphery, and means supporting said closures and said diaphragm in contact at their apexes.
7. In a transmitter, a light substantially 40 rigid double cone-shaped diaphragm, supporting members permitting substantially free translation of said diaphragm in response to sound vibrations a microphone unit, a light substantially rigid double conical 45 closure for said unit, the apex of which contacts with said diaphragm, and supporting means permitting substantially free translation of said closure in response to the action of said diaphragm.
8. In a transmitter, a light substantially 50 rigid double cone-shaped diaphragm, supporting means permitting substantially free translation of said diaphragm in response to sound waves, microphone units disposed on 55 each side of said diaphragm, a light substantially rigid double conical closure for each unit, the apexes of said closures contacting with the apexes of said diaphragm, and means permitting substantially free 60 translation of the closure in response to the vibrations transmitted from said diaphragm.
9. In a transmitter, a sound responsive diaphragm, a casing therefor, a plurality of 65 loosely arranged thin rings in the casing on each side of the diaphragm near its edge for seating the diaphragm, a carbon chamber, a light rigid closure for said chamber, a plurality of thin rings on each side of said closure near its edge for seating said closure, and means for supporting said diaphragm and said closure in operative relationship.
- In witness whereof, I hereunto subscribe my name this 11th day of October A. D., 75 1923.

CHARLES R. MOORE.
